CNIPA, Office Action issued on Jul. 5, 2023 for the corresponding Chinese Design Application No. 202230855048.6, along with its English outline, 2 pages.

Primary Examiner — Selina Sikder

(74) *Attorney, Agent, or Firm* — LUCAS & MERCANTI, LLP

(57) **CLAIM**

The ornamental design for a light emitting diode chip, as shown and described.

DESCRIPTION

FIG. 1 is a front view of the light emitting diode chip;
FIG. 2 is a back view thereof;
FIG. 3 is a top view thereof, a bottom view being a mirror image of the top view;
FIG. 4 is a right side view thereof, a left side view being a mirror image of the right side view;
FIG. 5 is another front view thereof;
FIG. 6 is a cross-sectional view thereof, taken along line 6-6 in FIG. 5; and,
FIG. 7 is a perspective view thereof.
The broken lines show environment and form no part of the claimed design.

1 Claim, 6 Drawing Sheets
